UNITED STATES PATENT OFFICE

JOAN HERMAN ANNE KRUIMEL, OF BLOEMENDAAL, NETHERLANDS

MACHINE FOR WINDING PAPER BELTS

Application filed October 31, 1931, Serial No. 572,307, and in Germany June 6, 1930.

The invention relates to a machine for winding paper belt, in which the belt arrives on a winding roll, which rests on a driving drum, from which it receives its motion, the 5 roll moving automatically from its initial position as it is wound with paper. The invention has for its object to facilitate the quick replacement of the winding rolls when one roll has been wound to the full diameter 10 and the belt has to be transferred to an empty roll, which is brought into the machine for that purpose, whereas the finished roll of paper is removed from the machine.

The accompanying drawing exemplifies 15 the subject of the invention in an embodiment.

A driving drum 1 is provided to drive the winding rolls 2 and 3 which touch the drum at its periphery, so that the rolls are rotated 20 with a uniform peripheral velocity through the action of friction. The empty winding roll 3 rests at the commencement of the winding operation with its trunnions 5 at both 25 ends in bearings 6, which are open at their upper halves and are each supported by a frame 20, which is slidably disposed in the direction of the paper movement. Both frames are supported at one extremity by 30 rollers running on tracks 7 and at their other extremity by bushings 8; they are drawn to one side by the action of the weights 9, which 35 exert a pull through the cables 10. This pull is transferred to the wheel 11 and from this through the axle to the gear wheels 13, which finally transmit the action of the weight to 40 racks 14 on the frame.

This mechanism ensures that both frames move in unison and that the winding roll moves always parallel to itself. This roll is 45 pressed by the pull of the weight against the driving drum 1 and driven by the action of friction. The winding roll 3 is in its initial position so far removed with its axis from the axis of the driving drum 1 in a direction corresponding to the direction of movement 50 of the paper 12 (arrow 21) that the roll moves against the pull exerted by the weights 9 in the direction 21 as its diameter increases due to the paper which is wound up; the axis of the roll is thus gradually removed from

the axis of the driving drum 1. In the track of the movement of the trunnions 5 of the winding roll 3 half bearings 16 are disposed on two supporting levers 15. These half bearings are so formed that they take up the 55 trunnions 5 of the winding roll 3, the levers 15 being to this end inclined against the direction of movement of the winding roll 3. The action of the mechanism described is the 60 following:

The paper belt 12 arrives on the empty winding roll 3 in the direction of the arrow 21 and is wound on this roll. The diameter of the roll 3 now increases due to the successive paper layers and moves accordingly 65 from its initial position, the half bearings 6 moving at the same time in the direction of the arrow 21, so that the trunnions 5 of the roll 3 move finally into the open bearings 16 70 of the levers 15. These levers now start to turn in the direction of the arrow 23 when the diameter of the roll further increases, by which action the trunnions 5 of the roll 3 are lifted from the open bearings 6, which 75 are in this way entirely freed.

Having thus been liberated the bearings 6 automatically slide back under the action of the weights 9 to their initial position, in which they are ready to receive another 80 empty winding roll.

The winding of the paper on the roll now carried by the levers is continued, till this roll has obtained the desired maximum diameter, so that it finds itself for instance at the 85 position indicated at 2, the trunnions then being situated at 4. At this moment the advancing paper belt is separated from the finished roll and led onto the empty winding roll 3, which lies in readiness, so that the 90 winding operation may be continued without interruption. The finished roll may now be taken from the bearings 16 of the levers 15, which have previously been immobilized by a bolt, for which removal a crane may be 95 used. The levers 15 are then returned to their initial position after removal of the bolt, in which they are again ready to take up the trunnions 5 of the fresh roll and the action may now be repeated. The extreme po- 100

sitions of the levers 15 are fixed by abutments 17, 18 and 19.

The construction indicated enables a nearly full roll to be quickly replaced by a fresh one. To this end it is merely necessary to place the fresh roll in position in the bearings 6, in which position it bears on the paper belt going to the nearly fully wound drum, and through this belt on the driving drum. The paper belt may now be fixed to the fresh roll and subsequently separated from the fully wound roll.

It is clear that the invention is not limited to the embodiment shown, but that modifications in the construction are possible, such as the replacement of the frames 20 by another set of levers moving in vertical planes.

What I claim is:

1. A machine for winding paper-webs, comprising a driving drum, a set of open bearings for carrying a winding roll, a horizontal frame supporting said open bearings slidable in the direction of the paper movement as said winding roll receives more paper, a second set of open bearings for receiving said winding roll from the first set of said open bearings, pivotal means supporting the second set of bearings in spaced relation from the first set of open bearings for shifting said second set from a position near the circumference of the driving drum, and weighted means for opposing the movement of the frame whereby to maintain uniform winding of the roll on the first set of open bearings.

2. Machine for winding paper-webs, comprising a driving drum, a set of open bearings for carrying a winding roll, leverage means movably supporting said bearings, for shifting the winding roll against an opposing force of gravity from a position near the circumference of said drum to a position more distant from said circumference, a second set of open bearings, and a pair of horizontal sliding guides, supporting this second set of bearings, so that they may be shifted from a first position, in which they are near to the circumference of the driving drum, but remote from the first mentioned position of the first set of bearings to a position in which they are further from the said circumference, the vertical plane through the axis of the second set of bearings moving between the axis of the driving drum and the axis of the said first set of bearings in its first-mentioned position.

3. A machine for winding paper-webs comprising a driving drum, a set of open bearings, balanced levers holding said bearings adapted to swing in vertical planes from a position near the driving drum to a position remote from this drum, a second set of open bearings, a pair of balanced horizontally sliding guides supporting the second set of bearings for shifting them from a posi-

tion between the vertical planes through the axis of the driving drum and through the nearest position of the said first set of bearings, to a position nearer to the said first set of bearings, a rack fixed to each sliding guide, a supported fixed axle, a pinion gear on said fixed axle, and weighted means for rotating the gear in a direction corresponding to the movement of the rack and guide whereby the second set of bearings moves towards its position nearest the driving drum.

4. In a machine for winding paper-webs, the combination consisting of a horizontal sliding frame, a set of open oppositely disposed bearings on said frame for a paper winding roll, a rack fixed to said frame, rotatable gearing means in engagement with said rack, counter-weighting means in connection with the gearing means actuatable upon the movement of the sliding frame for permitting winding of the roll carried on said open bearings, a second set of open bearings, and counterbalanced pivotal leverage means carrying said second set, for swinging over toward the first set of open bearings on the slide to carry the winding roll as it becomes larger and has moved a distance away from the vertical plane of the driving drum to permit the insertion of another paper winding roll on the first set of open bearings.

5. A machine for winding paper webs, comprising a driving drum for paper, a set of open bearings for carrying a paper winding roll, being shiftable against the opposing force of gravity from a position near the circumference of said drum to a position more distant from said drum, actuatable means for movably supporting said set of bearings when carrying the winding roll, said means being in spaced apart relation with respect to the driving drum, a second set of open bearings, horizontally mounted movable means for carrying the second set of bearings, said latter set being movable in the direction of movement of the paper on the driving drum, and weighted means in connection with the horizontally movable means opposing the movement of said horizontally mounted means for maintaining uniform pressure on the paper winding roll in its contact with the circumference of the driving drum.

6. A machine for winding paper webs, comprising a driving drum for paper, a set of open bearings carrying a paper roll, a pair of adjustable, pivotal levers movably supporting and carrying said bearings for shifting the same against gravity from a position near the circumference of said drum to a position more distant from said circumference, abutments on the levers at the ends opposite the bearings for limiting the movement of said pair of levers, the movement of said levers being normally confined to a position adjacent the circumference of

the driving drum as the paper is being wound on the roll, said levers being adapted to be fixed in vertical position when the roll is completely wound, a second set of open bearings, and a pair of horizontal sliding guides supporting said second set of bearings for shifting them from a position near the driving drum to a position near the first men-

tioned bearings, the vertical plane of said second set of bearings moving intermediate the axis of the driving drum and the axis of said first set of bearings in its first-mentioned position.

In testimony whereof I have signed my name to this specification. 70
